UNITED STATES PATENT OFFICE.

PETER F. NILSON, OF PHOENIX, ARIZONA TERRITORY, ASSIGNOR OF ONE-HALF TO BENJAMIN A. FICKAS, OF SAME PLACE.

TYPE-WRITING-MACHINE ATTACHMENT.

SPECIFICATION forming part of Letters Patent No. 554,831, dated February 18, 1896.

Application filed June 10, 1895. Serial No. 552,308. (No model.)

To all whom it may concern:

Be it known that I, PETER F. NILSON, a citizen of the United States, residing at Phoenix, Maricopa county, Territory of Arizona, have 5 invented an Improvement in Type-Writer Attachments; and I hereby declare the following to be a full, clear, and exact description of the same.

My invention relates to the general class of 10 type-writers and especially to an attachment therefor, the object of which is to enable the machine to write upon the pages of bound books, pamphlets, pads and other folded sheets, as well as upon ordinary sheets of 15 paper.

My invention consists in the novel holder 20 for the book, pamphlet, pad or paper whereby it is presented in proper position to the action of the type and in the necessary adjustments 25 and means for effecting them, whereby the position of the holder is varied as required, all of which I shall hereinafter describe and claim.

Referring to the accompanying drawings 25 for a more complete explanation of my invention, Figure 1 is a front elevation of my device. Fig. 2 is a rear elevation of the holder C. Fig. 3 is a horizontal section on line $\alpha\alpha$ of Fig. 1. Fig. 4 is a vertical section on line 30 $\gamma\gamma$ of Fig. 1. Fig. 5 is a detail of the back- ing-plate N.

As is a frame in which is mounted and adapted to travel sidewise a carriage B. The carriage is mounted in the frame in any suitable 35 manner, and for this purpose I have here shown it as being hung by suitable eyes b from a track a above, and moving by means of suitable guide-studs b' below in a slotted way a' in the bottom of the frame A. The 40 movement of the carriage may be effected by a spring or a weight, as may be desired; but for this purpose I have here shown a weight W connected with the carriage by a cord w which passes over suitable guides, and said weight 45 may be suitably housed in a tube w' at the side of the frame A.

Mounted in the carriage B and adapted to move vertically therein is a holder C. This consists of a main frame, to the front of which

is hinged a door-frame c, said door-frame being open in front and adapted to be held to the main frame by a suitable catch c' at the side opposite the hinges. This front or door frame has traversing it vertically holding- strips c², which are so arranged that the middle one occupies the central plane between the leaves of a book, pamphlet or pad, which is represented by D, while the side holding- strips pass over the margins of the pages of the book, pamphlet or pad, thereby leaving the central spaces of the leaves free for the reception of the type-impressions. The book, pamphlet or pad is held forward against these front holding-strips with a sufficient degree of pressure by means of a back plate E made in one or more sections, as the case may be, here shown as made in two sections, said plate or the sections thereof being adapted to be set up by means of pressure-screws F from the back of the holder-frame C.

By opening the door-frame c in front the book, pamphlet or pad may be placed in an open position with its back against the sections of the back plate, and then the door-frame is closed against it and is locked in position, whereby it is held with its sheets presented outwardly. It is to be understood that this holder-frame for the book may be of a size suitable for the book, pamphlet or pad intended to be written upon, and to this end it may be made adjustable or variable in size to receive different sizes of books. It is to be understood also that ordinary sheets of paper may be placed in this holder and written upon.

The necessary vertical movement of the holder, in order to present different lines to be written upon, is effected as follows: The main frame C of the holder is fitted to side guides b² in the carriage B, and said frame is suspended by a cord G passing up over a spring-controlled pulley g in the top of the carriage B, whereby the tendency is to pull the holder C upwardly constantly. On the side of the frame C is a feed-rack H with which a retaining-pawl I, pivoted on the carriage B and controlled by a spring i, normally engages. A feed-pawl J, pivoted to the carriage

B, has a tail extension *j*, which is adapted to lift up under an arm *i* of the pawl I so that as the feed-pawl J is thrown forwardly to engage with one of the teeth of the rack II its 5 tail extension, acting on the arm *i*, will withdraw the retaining-pawl I from said rack, and upon the next movement as the pawl J withdraws and the pawl I advances the holder will rise one tooth in the ordinary manner of 10 feeding mechanisms of this class. The feed-pawl J is operated by a hand-lever K pivoted to the side of the carriage B and connected with said pawl by a link *k*. The teeth of the rack II are so arranged that they will slip 15 down past the retaining-pawl I, so that the holder C may be pushed down to its lower-most limit to present the top of the page of the book or other sheet to be written upon to the action of the type. When one line is complete 20 the lever K is operated, and through the feeding mechanism the carriage is allowed to ascend one or more spaces to present a fresh line to be written upon.

The lateral movement of the holder with the 25 carriage B is effected in the ordinary manner of type-writing machines, and to illustrate this I have shown, in connection with my attachment, a form of key letter-bar and escape- 30 ment already known, and which constitute no part of my invention.

I have deemed it necessary to show but one key and letter-bar, though it is to be understood that a full set will be used.

L is the key and *l* the type or letter bar affected by the key and adapted to be thrown upwardly against the paper or book to be written upon. The key in pressing down depresses the space-bar M, which, through suitable connections, operates the pawl or pawls 40 indicated by *m* to engage with the escape- 45 ment or rack bar *m'* on the carriage below.

N is a plate, of metal, rubber, or other smooth hard material. It is adjustably hung by removable hooks from the top bar of the 45 holder-frame, and is adapted to be inserted behind the page, leaf, or sheet being written upon, to furnish a firm backing therefor.

Having thus described my invention, what 50 I claim as new, and desire to secure by Letters Patent, is—

1. In combination with the type and type-actuating mechanism of a type-writer, a vertically-disposed carriage having a track at its upper portion and a guide at its lower portion, 55 means actuated by the key mechanism of the type-writer for effecting the lateral travel of said carriage, a vertically-slidable holder suspended from said track, with its lower end engaging said guide, said holder adapted to 60 receive an open book, pamphlet, pad or sheet of paper, and present its face to the action of the type, and comprising a main frame, a front or door frame hingedly connected at one side with the main frame and adapted to be opened 65 and closed to receive and to permit the removal of the book, pamphlet, pad or paper,

and holding-strips across the front of the door-frame suitably disposed to present the paper to be written upon in a flat position, and means whereby the holder is intermittently moved upwardly in the carriage to provide for different lines. 70

2. In combination with the type and type-actuating mechanism of a type-writer, a vertically-disposed carriage, means actuated by 75 the key mechanism of the type-writer for effecting the lateral travel of said carriage, a vertically-slidable holder in the carriage adapted to receive an open book, pamphlet, pad or sheet of paper, and present its face to 80 the action of the type, said holder comprising a main frame, a front or door frame connected with the main frame and adapted to be opened and closed to receive and permit the removal of the book, pamphlet, pad, or paper, holding- 85 strips across the front of the door-frame suitably disposed to present the paper to be written upon in a flat position, a pressure-plate in the back of the holder-frame for holding the book, pamphlet, pad, or paper up to the 90 holder-strip, and means comprising a vertical rack on the holder-frame and a lever and pair of feeding-pawls whereby the holder is intermittently moved upwardly in the carriage to provide for different lines. 95

3. In combination with the keyboard and type mechanism of a type-writer, a laterally-movable carriage vertically disposed and actuated by the operation of the keys, a book, pamphlet, pad, or paper holder mounted and 100 adapted to slide vertically in said carriage, having a vertically-disposed rack, a spring-actuated cord or line suspending said holder and tending to raise it constantly, and a means comprising a retaining-pawl I pivoted to the 105 carriage, and controlled by a spring, a feed-pawl, also pivoted to said carriage, and having an extension adapted to operate the retaining-pawl, and a lever and a connection 110 therefrom to the retaining-pawl for effecting the intermittent vertical movement of said holder.

4. In combination with the keyboard and type mechanism of a type-writer, a laterally-movable carriage vertically disposed and actuated by the operation of the keys, a book, pamphlet, pad, or paper holder mounted and 115 adapted to slide vertically in said carriage, said holder consisting of a main frame, an open door-frame hinged to its front and adapted to receive and to permit the removal of a book, pamphlet, pad, or paper, suitable holding-strips across the front of said door-frame, and a pressure-plate behind to hold the book, pamphlet, pad or paper up to the holding- 120 strips, a spring-actuated cord or line suspending said holder and tending to raise it constantly, and a lever, a pair of feeding-pawls and a rack for effecting the intermittent vertical 125 movement of said holder. 130

5. The combination, with the type and type-actuating mechanism of a type-writing ma-

chine, the vertically-disposed slidable carriage and the vertically-slidable frame within the carriage, of a plate or sheet N having hooks at one end adapted to detachably engage the frame, said plate or sheet serving as a backing for the page, leaf, or sheet being written upon.

In witness whereof I have hereunto set my hand.

PETER F. NILSON.
